CONVEYOR INJECTOR COUPLING

Ralph J. McGinty, Salina, Kans., assignor to Wyatt Manufacturing Co., Inc., Salina, Kans., a corporation of Kansas

Filed Dec. 21, 1964, Ser. No. 83,097

Term of patent 14 years

(Cl. D55—1)

Fig.2.

Fig.1.

Fig.3.

Fig.4.

FIG. 1 is a top plan view of conveyor injector coupling, showing my new design;

FIG. 2 is a rear elevational view thereof;

FIG. 3 is a front elevational view thereof; and

FIG. 4 is a side elevational view of the conveyor injector coupling.

The appearance of the side opposite that shown in FIG. 4 is identical to that shown on FIG. 4.

I claim:

The ornamental design for a conveyor injector coupling, as shown and described.
